UNITED STATES PATENT OFFICE.

ROSE BINNER SCOGNAMILLO, OF NEW YORK, N. Y.

COMBINATION BUST-SUPPORTER AND SHOULDER-BRACE.

1,264,337.

Specification of Letters Patent. Patented Apr. 30, 1918.

Application filed February 11, 1913. Serial No. 747,652.

To all whom it may concern:

Be it known that I, ROSE BINNER Scognamillo, of New York, in the county of New York, and in the State of New York, have invented a certain new and useful Improvement in Combination Bust-Supporters and Shoulder-Braces, and do hereby declare that the following is a full, clear, and exact description thereof.

10 The object of my invention has been to provide a combination bust-supporter and shoulder brace which shall be effective and comfortable, and capable of being made attractive in appearance, and to such ends my 15 invention consists in the combined bust-supporter and shoulder brace hereinafter specified.

In the accompanying drawing, the figure 20 is a perspective view of a combined bust-supporter and shoulder brace embodying my invention.

While I have chosen, as an illustration of my invention, that embodiment which is the best embodiment known to me, such embodiment 25 is to be regarded as typical only of many possible embodiments.

The combined bust supporter and shoulder brace illustrated in the drawing comprises a front piece 4, preferably of inelastic material and extending to each side. Back pieces 2 and 3 connect front piece 4 with stiffened eyelet pieces. These back pieces 30 preferably are formed of elastic strips 7 and 8 running diagonally downward from said 35 eyelet pieces. Bust supporting pockets 5, preferably of lace, are secured to the upper edge of inelastic piece 4, and each pocket is gathered at the top to give the desired shape to the pocket. It will be noted in the 40 embodiment disclosed the pockets are substantially triangular in shape. The pockets are secured together detachably by any desired means as by buttons and loops. Each pocket is secured at its outer lower corner 45 to back pieces 2 and 3 respectively. An elastic insert 1 is provided at the bottom of front piece 4 which aids in holding the supporter in position and from riding up, without sacrificing the advantages derived from

inelastic front piece 4 as an equalizer of the 50 pull from the elastic back pieces 2 and 3 and as an inelastic foundation for the pockets 5. Shoulder brace straps are secured to the back pieces at, and adjacent to, the eyelet pieces, and the other end of each strap is 55 secured to the top of a bust receiving pocket.

The disposition of the elastic back pieces diagonally permits the utilization of a portion of their elasticity in the direction of pull imparted by the shoulder straps. The 60 inelastic member at the front retains the garment in position against the pull of the elastic side pieces and also maintains the shape of the bust receiving pockets. The stiffened eyelet pieces maintain the back in 65 upright position without wrinkling and aid in equalizing the elasticity of the back pieces. The elastic insert at the bottom insures a close fit and prevents the garment from riding up.

It will be observed that my combined bust-supporter and shoulder brace has, among others, the following advantages:—

It can be used with a very low corset or with no corset at all and still preserve the 75 shape of the bust and erectness of the shoulders. While this very desirable result is attained, the construction is such that it affords ease and freedom of movement. While the bust-supporting parts will effectively 80 perform their function, they can yet be made of light and attractive material, such as lace.

I claim—

1. A combined bust supporter and shoulder brace formed with an inelastic front piece, independent bust receiving pockets secured to said front piece and gathered at the top to form substantially a triangular-shaped pocket, means to secure together the 90 inner edges of said triangular pieces, and means to secure said supporter on the body.

2. In a combined bust supporter and shoulder brace formed with an inelastic front piece provided with an elastic insert 95 at the bottom thereof, stiffened eyelet pieces, diagonally extending elastic back pieces secured to said front piece and to said stiff-

ened eyelet pieces, bust receiving pockets secured flat to the top of said front piece and gathered at the top to form triangular-shaped pockets, and shoulder straps or braces secured to the top of said pockets and to said back pieces in such a manner that the direction of stretch of each back piece will lie substantially in the direction of pull

of the shoulder strap or brace on the opposite side of said supporter.

In testimony that I claim the foregoing I have hereunto set my hand.

ROSE BINNER SCOGNAMILLO.
